STEREOPTICON SLIDE

Paul M. Meadows, Haworth, N. J.

Application September 29, 1936, Serial No. 103,669

3 Claims. (Cl. 88—28)

This invention relates to improvements in slides or mats for use in stereopticon machines.

Stereopticon slides and mats have recently come into extensive use as an aid in instructing children to draw and write. In one case, for example, the slide is a small plate of frosted or ground glass. The child writes or draws on the frosted or ground surface and the result of the child's efforts is projected on a screen through the instrumentality of a stereopticon machine. An interest is created and maintained in the child by the knowledge that his work will be displayed in realistic and magnified form on the screen before his classmates. The teacher may with facility and for the benefit of the entire class, point out existing errors, mistakes or other faulty execution or require members of the class to do so. The child is thus taught to remedy his mistakes and to be neat and careful in the execution of his work to mitigate or minimize criticism.

The child should be permitted to allow his mind to be centered on the execution of his work and not to be deviated into other channels, such as, manipulation or requirement of careful handling, of the slide, or determination as to the areal limits within which the work is to be executed. Therefore, the slide or mat should be very simple in construction, light but of sufficient body to make it self-sustaining, and non-fragile, and should be provided with integral means for defining the area or field to be projected so that the child, without giving much thought to the matter will confine his writing or drawing within that given area.

From an economical standpoint, such slide should be reusable. Since such a slide is frequently used for tracing purposes it should be of such character that the parallax of the object to be traced due to the slide should be reduced to a minimum.

The prior art discloses, in addition to ground or frosted glass plate, mats made of very thin transparent cellulosic material having a body which is not self-sustaining. This type is particularly used for preparing titles, diagrams, maps, etc., for illustrated lectures. These mats not being self-sustaining have to be supported between two clear glass plates. This preparation consumes time, and the whole is dangerous by reason of possible breakage and requires careful handling to prevent injury to the operator; and, of course, undesirable for use by children. Furthermore, these mats lack stability, cannot be reused for other subjects. On account of its unmatted surface it is difficult to write or draw thereon.

It is an object of the present invention to provide a very practical, efficient, economical and simple translucent plate which can be written or drawn upon and be used as a slide or mat for a stereopticon.

It is a further object of this invention to provide a stereopticon slide or mat in the form of a substantially thin, but self-sustaining, flexible, non-fragile plate having a matted surface adapted to receive markings and impressions, and an integral opaque marginal frame or mask defining a field or area upon which the markings and impressions may be made, and which may be further characterized by having signal or visual indicating means on a side edge for guiding and adjusting the slide relative to the stereopticon.

The above and further objects, advantages and purposes will be understood from a consideration of the following detailed description, taken in connection with the accompanying drawing forming part of this specification, with the further understanding that while the drawing shows a practical form of the invention, the latter is not confined to any strict conformity with the showing of the drawing, but may be changed and modified so long as such changes and modifications come within the scope of the appended claims.

In the drawing:

Fig. 1 is a plan view of a slide with its matted surface uppermost and bearing a drawn illustration.

Fig. 2 is a plan view of the slide blank with its obverse side uppermost.

Fig. 3 is a sectional view taken along line 3—3 of Fig. 2.

The drawing shows an example of slide embodying the invention.

Slide 10 is a substantially thin but self-sustaining, non-fragile, flexible plate preferably made of a material such as, for example, celluloid, pyroxylin, other ethers and ethers of cellulose, or horn-like materials having approximately the physical properties of cellulosic materials. Cellulose acetate forms a suitable substance for the slide blank.

The slide 10 is provided with a matted or dull-ground like surface B capable of receiving and retaining marks, designs, drawings or other markings, impressions and characters made with pencil, crayon, ink, water color, or the like, but which surface may be substantially cleared of such characters by suitable means, such as, for instance, a damp cloth or sponge. By means of its flexibility the slide may be inserted in a typewriter.

Slide 10 is preferably made of a thickness that

will not cause appreciable parallax of the object to be traced, if so desired.

Preferably provided on the matted or dull surface B of the plate 10 is an opaque marginal frame, border or mask 11. This frame or mask 11 is made integral with the slide material as by being printed or stencilled thereon, and serves a two-fold purpose, namely, to define the field or area 12 upon which the work may be executed 5 so that the same may be wholly exposed for projection upon the screen, and to permit the work to stand out by contrast therewith upon the screen.

Upon a margin or side 16 of the slide there 15 may be carried indicia or characters, such as, for example, at one end, a star, an arrow with its head pointed in the direction of the star and adjacent the arrow, the word "Thumb", generally indicated by the numeral 13; and at the 20 other end an arrow pointed in the opposite direction to the previously mentioned arrow and adjacent this latter arrow the word "Top", generally indicated by the numeral 14. Any other signal or visual indicating means may be employed.

When the slide is inserted in the stereoptican machine, the polished or unmatted side indicated in Fig. 2 by the letter A will be toward the screen and the dull and matted side B carrying the 30 drawing or other character 15 will be toward the light source of the machine.

In order to assure proper insertion of the slide in the machine, the characters or indicia 13 are arranged at the bottom of edge 16, and the characters or indicia 14 at the top thereof. The slide 35 is gripped at the bottom of edge 16 between the thumb and forefinger of the hand for insertion into the machine.

The edge 16 may be provided with other characters, as for example, the trade-mark "Slide-craft" indicated by the numeral 17; or the same 40 may be provided with instructions as to the use of the slide. Although the characters or indicia are shown as being opaque against a translucent or transparent background, any other suitable 45 arrangement may be employed, as by way of example, transparent characters or indicia against an opaque background. The picture 15 can be prepared in pencil, ink, crayon, water color, or 50 the like, and can easily be removed by washing, leaving the slide clear and clean for repeat use.

While I have here shown what I believe to be a simple and efficient form of the invention it is

to be understood that certain alterations in the details of construction such as may be developed through the exigencies of use may be resorted to without transcending the scope of the invention as defined by the appended claims.

Having described my invention what I claim as new and desire to secure by Letters Patent, is:—

1. As an article of manufacture, a one-piece single sheet stereopticon slide comprising a self-sustaining non-fragile, flexible plate of substantially transparent material which is roughened on one side to render it substantially translucent and to receive markings thereon, and an opaque marginal frame on the sheet and applied integral therewith defining a field or area on the roughened sheet within which markings may be applied by a marking device to said roughened surface and to cause said markings to stand out in contrast with the frame when projected on a screen.

2. As an article of manufacture, a one-piece single sheet stereopticon slide comprising a self-sustaining, non-fragile flexible plate of substantially transparent material having the physical properties of cellulosic material which plate is roughened on one side to render it substantially translucent and to receive removable markings thereon, and an opaque marginal frame printed on the sheet defining a field or area on the roughened sheet within which markings may be applied by a marking device to said roughened surface and to cause said markings to stand out in contrast with the frame when projected on a screen.

3. As an article of manufacture, a one-piece single sheet stereopticon slide comprising a self-sustaining, non-fragile flexible plate of substantially transparent material having the physical properties of cellulosic material which plate is roughened on one side to render it substantially translucent and to receive removable markings thereon, an opaque marginal frame printed on the sheet defining a field or area on the roughened sheet within which markings may be applied by a marking device to said roughened surface and to cause said markings to stand out in contrast with the frame when projected on a screen, and a marginal border along at least one edge of said sheet with indicia thereon to indicate 40 positioning of the plate for insertion into a stereopticon.

PAUL M. MEADOWS.
